CLAIM

The ornamental design for a facial cleansing device, as shown and described.

DESCRIPTION

The patent or application file contains at least one drawing executed in color. Copies of this patent or patent application publication with color drawing(s) will be provided by the Office upon request and payment of the necessary fee.

1.1 is a front elevational view of a facial cleansing device showing my design;

1.2 is a rear elevational view thereof;

1.3 is a left side elevational view thereof;

1.4 is a right side elevational view thereof;

1.5 is a top plan view thereof; and

1.6 is a bottom plan view thereof;

2.1 is a front elevational view of a facial cleansing device showing my design;

2.2 is a rear elevational view thereof;

2.3 is a left side elevational view thereof;

2.4 is a right side elevational view thereof;

2.5 is a top plan view thereof; and

2.6 is a bottom plan view thereof;

5.1 is a front perspective view of a facial cleansing device showing my design;

5.2 is a front elevational view thereof;

5.3 is a rear elevational view thereof;

5.4 is a left side elevational view thereof;

5.5 is a right side elevational view thereof;

5.6 is a top plan view thereof; and

5.7 is a bottom plan view thereof;

6.1 is a front perspective view of a facial cleansing device showing my design;

6.2 is a front, elevational view thereof;

6.3 is a rear elevational view thereof;

6.4 is a left side elevational view thereof;

6.5 is a right side elevational view thereof;

6.6 is a top plan view thereof; and

6.7 is a bottom plan view thereof.

In Reproductions **1.1-1.6**, the color blue is for the purpose of illustrating environment only. In Reproductions **5.1-5.7**, the broken lines are for the purpose of illustrating environment

(Continued)

only. In **1.1-1.6** and **5.1-5.7** the features shown in the color blue and in broken lines form no part of the claimed design.
